UNITED STATES PATENT OFFICE.

CLIFFORD C. CARPENTER, OF SEATTLE, WASHINGTON.

ELECTRIC-LIGHT SHADE.

981,531.

Specification of Letters Patent.

Patented Jan. 10, 1911.

Application filed July 26, 1910. Serial No. 573,915.

To all whom it may concern:

Be it known that I, CLIFFORD C. CARPENTER, a citizen of the United States, residing at Seattle, in the county of King and State of Washington, have invented certain new and useful Improvements in Electric-Light Shades, of which the following is a specification.

The object of this invention is to provide an exceedingly simple and inexpensive form of shade adapted to be readily attached to and detached from the sockets to which ordinary electric light bulbs are secured.

The invention involves particularly a shade comprising a suitable opaque body which is carried detachably by a simple form of clamp, the latter being conveniently arranged for engagement with the light socket aforesaid.

For a full understanding of the invention, reference is to be had to the following detail description and the accompanying drawings, in which—

Figure 1 is a view showing an ordinary electric light bulb and socket having the invention supported thereon, the shade being shown in section; Fig. 2 is an elevation of the shade and its supporting member, the clamp members being omitted; Fig. 3 is a plan view showing more particularly the clamp device; Fig. 4 is a section taken about on the line 4—4 of Fig. 2, and Fig. 5 is a modification, being a view similar to Fig. 1.

Throughout the following description and on the several figures of the drawings similar parts are referred to by like reference characters.

In the drawings, 1 denotes the socket adapted to receive the electric light bulb 2, the latter being adapted to be screwed into the socket in the customary way and containing the usual filament 3.

The shade attachment comprising this invention is composed of four essential parts, namely, the shade member shown at 4, a supporting member 5 secured thereto, and two clamp members 6.

It is contemplated that the shade 4 may be made of any suitable opaque material or substance, but said shade is preferably formed from sheet metal and is of concavo-convex form in cross section. An opening is formed at the central portion of the shade by pressing the metal outwardly as shown at 4' and the supporting member 5 consists of

a length of wire, the lower end of which is bent upwardly to provide a hook 7 which passes through the central opening of the shade 4. The hook 7 is of peculiar shape 60 in order that it may be so engaged with the shade 4 as to prevent looseness of the latter when suspended adjacent to the light by means of the member 5. At its upper portion, the hook 7 is formed with a bend 7', 65 providing a recess on the inner side of the hook, and adjacent to said recess the metal or material from which the shade 4 is made is formed with a U-shaped projection 4'', the latter being preferably pressed outwardly from the metal as shown clearly in the drawings. When the shade 4 is supported on the member 5, the bend 7' of the hook 7 engages over the lower portion of the projection 4'', and the upper extremity of the 75 hook is seated between the sides of said projection, thereby preventing accidental upward displacement of the shade from the member 5, as well as lateral play of the shade.

The supporting member 5 has its upper end passing through complementary pivot lugs integral with each of the clamping members 6, thereby pivotally connecting said clamping members. The upper peripheral portion of 85 the shade 4 is cut out or recessed as shown at 8 to provide a clearance space for the finger pieces 6' of the clamping members 6. The cut out portion of the shade may also serve as a clearance space to receive the body of 90 the socket 1 in the manner shown in the modification in Fig. 5 should it be desired that the shade illustrated in said figure be permitted to assume the position shown.

The structure illustrated in Fig. 5 is substantially the same as hereinbefore described excepting that the clamping members and the shade are arranged in slightly different relative positions, and the hook 7a of the supporting member 5a is of slightly different form, having the protuberance 5b to engage the central apertured portion of the shade 4 to subserve the rigidity of the connection between the supporting wire or member 5a and said shade.

A spring 9 is interposed between the finger pieces 6' of the clamp members 6 to normally cause the latter to move toward one another.

Having thus described the invention, what 116 is claimed as new is:

1. A shade attachment of the class de-

- scribed comprising a shade having an aperture therein, a supporting member for the shade comprising a wire having one end bent to form a hook passing through the 5 aperture, a clamping device connected with said supporting member, the shade being provided with a projection engaging the hook of the supporting member to prevent play of the shade when mounted thereon.
- 10 2. A shade attachment comprising a shade provided with an aperture therein, a supporting member consisting of a piece of wire having one end bent upon itself to form a hook passing through the aperture, said hook being provided with a depression in its 15 length, the shade being formed with a U-shaped projection pressed outwardly therefrom and the curved end of which is re-

ceived in the recess of the hook preventing accidental displacement of the shade from 20 the supporting member, the sides of the U-shaped projection being arranged at opposite sides of the hook to prevent lateral play of the shade suspended thereon, and clamping members pivotally mounted on the 25 upper end of the supporting member aforesaid, the shade being recessed at its upper portion adjacent to the clamp members to form a clearance space as specified.

In testimony whereof I affix my signature 30 in presence of two witnesses.

CLIFFORD C. CARPENTER.
